CLAIM

The ornamental design for an ice cream dispensing device or similar article, as shown and described.

DESCRIPTION

FIG. 1 is a perspective view of an ice cream dispensing device or similar article showing my new design;

FIG. 2 is a left side elevational view thereof, the opposite side being a mirror image;

FIG. 3 is a top plan view thereof;

FIG. 4 is a bottom plan view thereof;

FIG. 5 is a front elevational view thereof; and

FIG. 6 is a rear elevational view thereof.
